UNITED STATES PATENT OFFICE

2,044,457

HEAT EXCHANGER

Fred M. Young, Racine, Wis.

Application November 25, 1935, Serial No. 51,452

5 Claims. (Cl. 257—151)

My invention relates particularly to air blast heating and cooling units, and provides means whereby units may be readily assembled in shapes and sizes suitable for the various equipment needs, 5 and a device that will operate efficiently.

One of the objects of my invention is to provide a design which may be manufactured or shipped in a number of sections and bolted together when being installed, without the use of 10 pipes or fittings, thus to facilitate manufacturing, shipping and installing operations.

Another object is to provide a number of sections having means to pass the heating or cooling medium through the sections in series sinuously 15 from the inlet to the outlet through direct openings between the sections, thus to reduce friction and insure free and equal flow through the tubes of the sections.

A further object is to provide a unit which may 20 be operated on the counter flow principle.

It is a further object to provide means whereby the sections are held together through stuffing boxes and semi-resilient packing rings, thus to insure against loose joints, leaks and trouble 25 from unequal expansion and contraction.

Another object of my invention is to provide a unit which will occupy minimum space and wherein individual sections may be easily removed and replaced, and whereby very few headers may 30 be used with which to make up an almost innumerable number of sections of varying sizes; also whereby very few sections may answer with which to make up units suitable for an almost innumerable number of installations, thus to simplify and 35 cheapen manufacturing and installing problems.

To these and other useful ends my invention consists of matter hereinafter set forth and claimed and shown in the accompanying drawings in which:

40 Figure 1 is a front elevation of my improved device.

Figure 2 is a side elevation of the device shown in Figure 1, comprising 4 sections and 2 rows of tubes in each section.

45 Figure 3 is an enlarged fractional section taken on line 3—3 of Figure 1.

Figure 4 is a fractional side view illustrating a unit having 2 sections and 3 rows of tubes to each section.

50 Figure 5 is a diagrammatic drawing illustrating a unit having 3 sections and 2 rows of tubes to each section.

Figure 6 is a diagrammatic drawing illustrating a 4 section unit as shown in Figure 2.

55 Figure 7 is a diagrammatic drawing illustrating

ing a 4 section unit, 3 sections having 2 rows of tubes each and 1 section having 1 row of tubes.

As thus illustrated in Figures 1, 2, 3 and 6, my improved heat exchanger comprises four sections, these sections being designated by reference characters A, B, C and D. A designates No. 1 or the inlet section. As clearly illustrated in Figures 2, 3 and 6 section A comprises inlet header 10 and outlet header 11 and the tubes therebetween are designated by reference numeral 12. The 10 tube ends are expanded and held in openings in the headers preferably by means of ferrules 13.

All of the headers are provided with threaded openings 14, each registering with a tube whereby the tube ends and ferrules may be expanded 15 in the usual manner after which the openings are closed by means of suitable screw threaded plugs. In the outside face of headers 10 and 11, preferably three inlet openings 15 are provided, the center one in header 10 being closed by means of 20 the screw threaded plug 16. These three openings are used for inlet pipe connections and any one or more of these openings may be used for this purpose.

Header 11 may be exactly like header 10 insofar as concerns the foregoing except that all three openings 15 are sealed by plugs 16. The inner faces of these headers are provided with two circular projections 17 which are exactly opposite projections 18—18, (see dotted lines in Figure 1). These projections are machine faced. An opening 19 is provided in the center of lugs 17 in header 10 and is of a size which will loosely embrace bolt 20. Projections 18 on headers 10 and 11 are provided with openings 21 which will 35 loosely embrace bolt 20. Openings 21 are counter sunk from the outside forming pockets 22 for which I provide a semi-resilient packing ring 23. I also provide a suitably shaped sleeve 24 which, when seated firmly on ring 23, will protrude past 40 the surface of projections 18. Bolts 20 are threaded at each end as indicated; thus nut 25 will answer with which to compress ring 23 and seal the opening and also provide means whereby the various sections of the unit are bound together as will hereinafter appear.

Section D is exactly like section A except it is reversed as indicated. It will be seen by referring to Figure 4 that enlarged openings 30 are 50 provided in headers 11. One end of sleeve 31 is pressed into the opening in one header the other end being made slightly smaller and will be loosely embraced by the opening in the adjacent header (see Figure 3); thus it will be seen that 55

when assembling the units as shown in Figure 4, the bolts 20 will answer as dowels or positioning means between headers 10 and that the sleeves 31 will answer as dowels or positioning means for headers 11, the openings 30 being large enough for the passage of the heating or cooling means from one header to the other. Thus in the assembly shown in Figure 4, the heating or cooling medium may enter one of headers 10, pass to header 11 through the connecting tubes and thence through openings 30 and through the tubes of the other section. I provide gaskets 31a and 19a with which to seal the joints between the various headers.

In Figure 4 I have illustrated as described, a two section unit and the end sections from which 2, 4, 5 or 6 section units may be constructed as follows:

In Figures 2 and 6 I illustrate a four section unit, a fraction of which is shown in Figure 3, considerably enlarged, wherein the details of the intervening headers used on sections B and C are shown. At this point attention is called to the fact that the intervening headers are duplicates, but they are positioned whereby the enlarged openings 30 are paired as illustrated; but these openings at the other end of the section are on the opposite side of the section, as clearly illustrated in Figures 6 and 7, and openings 19 are paired as shown. It will be noted that similar numerals are applied to like parts in the various sections. Thus as will hereinafter appear, any number of intervening sections may be placed between the inlet and outlet sections, it being necessary only to turn intervening sections oppositely and position the headers oppositely on each section whereby to connect all of the sections in series as clearly illustrated in Figures 5, 6 and 7. In Figures 2, 3, 5, 6 and 7 intervening headers are similar and therefore reference numeral 35 is used to designate these headers, both sides having preferably projections which are similar to projections 11 on headers 10 and 11, one side however, having openings 30 and the other side having openings 19, the object of these projections being to simplify the surface milling operations. The advantage of this design is that the projections may be machined in one operation by straddle milling.

Clearly units A and D of Figure 2, may provide the inlet and outlet headers for the assemblies shown in Figures 4, 5 and 6. In Figure 5 the outlet section is turned end for end in order to provide the proper set up for the three section unit. In Figure 7 the outlet section may be exactly like section D of Figure 2 except that there is but one row of tubes but the headers therefor may be made somewhat narrower if desired.

Three rows of tubes may be placed in headers 10 and 11 by staggering the rows. In any event either header may be made suitable for either one, two or three rows of tubes or separate headers of a proper width may be supplied. In some installations an odd number of tubes may be found desirable. This may be accomplished as in Figure 7, or by using a three and a two row section with which to provide a five row unit. If however, a unit as in Figure 4 is desired having five rows, the outlet section in the assembly may be supplied with two rows of tubes as shown in Figures 5 and 6. Clearly therefore, an innumerable number of combinations are possible. Generally however, the desired number of tubes may be made possible by simply using longer or shorter headers in order to avoid odd combina-

tions of sections; for example, when it is desired to locate the outlet on the same end of the unit as the inlet, this must be accomplished by providing either two, four or six sections. If however, it is desired to place the outlet on the opposite end from the inlet, there should be either three or five sections of the desired number of rows of tubes having sections of a suitable length and width and the correct aggregate number of tubes to produce the desired results. Obviously many different combinations, too numerous to mention, are possible with applicant's headers and means for making up sections and units therefrom; for example, an assembly as shown in Figure 4 may be made by using headers 11 at both ends of the sections; thus there would be provided openings 30 between each pair of tubes as indicated by dotted lines and by suitably positioning plugs 16, the heating or cooling medium may be caused to pass through the sections in parallel.

Clearly when desired, the sections may be completed and shipped to their destination in separate crates with full assurance that any person, skilled in erecting and installing units of the class, will be able to assemble and install applicant's unit in a satisfactory manner and at a minimum cost. Bolts 20 may be of a generous diameter and they, the gaskets and end packing rings may be of a material which will resist deterioration.

It will be seen that the outstanding advantages of applicant's device are, resilient finding means, convenience in manufacture and assembling, that the flow of heating or cooling medium may be through the proper number of tubes which are 35 in series and therefore the benefit from equal distribution of liquid in the tubes of a section, may be assured and the counter flow heat transfer principle made available.

Having thus shown and described the preferred form of my invention, I claim:

1. A heat exchanger comprising a number of sections, each consisting of two headers and circulating tubes therebetween, said headers being bound together by means of bolts passing therethrough, gaskets between said headers surrounding said bolts, enlarged openings positioned alternately with closely embracing openings surrounding said bolts between certain pairs of headers, whereby the heating or cooling medium will pass serially through said sections and enlarged openings, said bolts at their ends having stuffing boxes with semi-resilient packing rings and means whereby said sections will be bound together through said rings.

2. A heat transfer device comprising a number of sections, each consisting of two headers and circulating tubes therebetween, said headers being bound together by means of bolts passing therethrough, gaskets between said headers surrounding said bolts, enlarged openings having centering sleeves surrounding said bolts, whereby the heating or cooling means may pass from one header to the other, a stuffing box having a semi-resilient packing ring at each said bolt ends, sleeves and holding means at the ends of said bolts, whereby said headers are held together through said packing ring.

3. A heat transfer device comprising a number of sections, each having two headers and circulating tubes therebetween, said headers being bound together by means of bolts passing therethrough, gaskets between said headers surrounding said bolts, stuffing boxes having semi-resilient packing rings and sleeves each surrounding said bolt ends,

holding means on said bolt ends resting on said sleeves, whereby said headers are held together through pressure on said packing rings, inlet and outlet connections in certain headers and enlarged openings surrounding said bolts between certain pairs of headers, whereby the heating or cooling medium may pass from the inlet to the outlet through said sections in series.

4. A heat transfer device comprising a number of sections, each consisting of two headers and circulating tubes therebetween, said headers being bound together by means of bolts passing therethrough, stuffing boxes having semi-resilient packing rings in said headers at each bolt end and having sleeves and nuts, whereby said headers are held together through said packing rings.

5. A heat transfer device comprising two sections, each consisting of two headers and circulating tubes therebetween, said headers being bound together by means of bolts passing therethrough, gaskets between said headers surrounding said bolts, inlet and outlet connections in adjacent headers and enlarged openings surrounding the bolts of the other headers, whereby the heating or cooling medium may pass through said tubes and said other headers, a stuffing box having semi-resilient packing rings in said headers and sleeves thereon at each bolt end, forming a rest for nuts thereon, whereby said headers are held together through said packing rings.
